ATTORNEYS.

UNITED STATES PATENT OFFICE.

LEVI STUCK, OF HART, MICHIGAN, ASSIGNOR TO H. D. JUSTI, OF PHILADELPHIA, PENNSYLVANIA.

DENTAL CHAIR.

SPECIFICATION forming part of Letters Patent No. 381,040, dated April 10, 1888.

Application filed November 2, 1887. Serial No. 254,054. (No model.)

To all whom it may concern:

Be it known that I, LEVI STUCK, a citizen of the United States, residing at Hart, in the county of Oceana, State of Michigan, have 5 invented a new and useful Improvement in Dental Chairs, which improvement is fully set forth in the following specification and accompanying drawings.

My invention consists of improvements in 10 dental chairs, as herein set forth and claimed.

Figure 1 represents a partial side elevation and partial vertical section of a portion of a dental chair embodying my invention. Fig. 2 represents a horizontal section on line xx , Fig. 1, on an enlarged scale. Fig. 3 represents a horizontal section on line yy , Fig. 1, on an enlarged scale. Fig. 4 represents a vertical section on line zz , Fig. 2. Fig. 5 represents a vertical section on line $z'z'$, Fig. 3. Fig. 6 20 represents a side elevation of a detached portion.

Similar letters of reference indicate corresponding parts in the several figures.

Referring to the drawings, A represents the 25 seat of a dental chair, but may be that of a barber's or other chair.

B represents a stem or standard which is secured to and depends from the seat A and enters a casing, C, which may be of cylindrical 30 or other form.

Freely encircling the standard B is an annulus, D, which is located near the top thereof, and has at one portion of its periphery a lip, E, which rests in a recess or groove of the 35 cross-bar F, the latter extending horizontally within the casing C and being secured thereto. Pivoted to the annulus opposite to the lip E is a rod, G, which passes to the bottom of the casing, where it is pivoted to or freely connected with a pedal or foot-lever, H, which is 40 accessible outside of the casing, and when depressed serves to elevate the annulus. The inner periphery of the annulus is oblique or inclined, so as to present two biting-edges or 45 teeth, J J, respectively, at the upper and lower sides of said peripheries.

Below the annulus D is an annulus, K, which freely encircles the standard B and rests on a cross-bar, L, the latter extending 50 horizontally within the casing C and being se-

cured thereto and being substantially parallel to the bar F. The inner periphery of said annulus K is toothed, as at K', so as to bite said standard B. Bearing against the under side of said annulus K, or pivoted thereto, is a 55 link, M, to which is pivoted a pedal or handle-lever, N, which has its bearings on the casing C and is accessible outside of the same.

Connected with the pedal H and base of the casing is a spring, P. Connected with the annulus K and base of the casing is a spring, Q, 60 said springs exerting downward pressure on the annuli D and K and serving to restore the same to their normal positions. The inner periphery of the annulus D is faced with steel 65 blocks J, so as to take firm hold of the standard, the body of said annulus being brass, cast-iron, or other metal. The annulus K is preferably formed entirely of steel.

The standard B is guided by the top cap of 70 the casing C and an eye, S, which is secured to the bottom of said standard and freely fitted on an upright rod, T, which is secured to the base of the casing and the cross-bar F, whereby said eye slides on said rod in the ascending 75 and descending motions of the standard.

The operation is as follows: When the seat is to be raised, the lever N is depressed, whereby one side of the annulus K is raised and the teeth K' at said side bite the standard B. The 80 ascending annulus thus carries the standard with it until the desired height is obtained, when the lever is let go, and the annulus then drops to its normal position on the cross-bar L. The standard now being free of the annulus K is caught by the annulus D, which, as 85 has been stated, is supported on one side by the cross-bar F and forced down on the opposite side by the spring P, the annulus assuming an oblique position downward, so that 90 the teeth J bite the standard and thereby prevent descent of the same, the seat thus being held in its elevated position. When the seat is to be lowered, the pedal H is depressed, whereby the annulus is raised and brought to 95 a horizontal or approximately horizontal position, whereby the teeth J are withdrawn from the standard, and the latter then drops and the seat returns to its normal position.

The extent of elevation of the seat is regu- 100

lated or adjusted by the lever N both in the throw of the same and the number of times said lever is worked.

The casing C incloses the annuli or clutches 5 D and K and other parts of the device, also providing bearings for the levers H N and forming a proper finish for the chair below the seat thereof.

I am aware that it is not new to construct a 10 lifting device wherein an annulus is operated by means of a pivoted lever so as to raise a rod, the device having also a second annulus operated by gravity for holding the said rod in place, the said second annulus being released 15 from the rod by means of a second rod operated by a treadle and adapted to be brought in contact with the said second annulus, raising the side thereof which engages with the lifting-rod, and such I do not claim; but I am 20 not aware that the construction as herein shown and described is old—that is, the holding-annulus having a lip resting in a notch in a cross-bar of the casing and the opposite side of the said annulus being pivoted to the operating-rod, whereby the operation is reliably and certainly effected without jar or shock.

Having thus described my invention, what I claim as new, and desire to secure by Letters Patent, is—

30 1. A dental chair having a seat with a depending standard, a casing in the top opening of which said standard is inserted, the cross-bar F, secured to and within said casing, the annulus D, surrounding said standard and having a lip, E, resting on said cross-bar F, and also having its inner periphery inclined, the

rod G, pivoted to the side of the annulus D opposite to the lip E, the treadle projecting through an opening in the casing C and having its inner end secured to the lower end of 40 rod G, and the spring P, secured to the inner arm of said treadle and to the base, said parts being combined substantially as and for the purpose set forth.

2. A dental chair having a seat with depending standard, a case in which said standard is inserted, a recessed cross-bar within said casing, an annulus surrounding said standard and having a lip resting in the recess of said cross-bar, the inner periphery of said annulus being 50 inclined, a rod pivotally attached to the side of the annulus opposite from the lip, and a treadle connected with said rod, said parts being combined substantially as and for the purpose set forth.

3. A dental chair having a seat with standard and a casing in which said standard is inserted, the cross-bar F, the annulus D, with lip E and inclined inner periphery, the rod G, pivotally attached to said annulus at the 60 side opposite the said lip, the treadle H, connected with said rod G, the cross-bar L, the annulus K, with teeth K' on one side of the inner periphery, the link M, secured to said annulus K on the same side thereof as the teeth 65 K', and the lever N, with spring Q, said parts being combined substantially as and for the purpose set forth.

LEVI STUCK.
